UNITED STATES PATENT OFFICE.

MOSES H. HAMILTON, OF FORREST CITY, ARKANSAS.

AIR-PUMP.

1,390,782.

Specification of Letters Patent. Patented Sept. 13, 1921.

Application filed December 3, 1918. Serial No. 342,111.

To all whom it may concern:

Be it known that I, MOSES H. HAMILTON, a citizen of the United States, residing at Forrest City, in the county of St. Francis 5 and State of Arkansas, have invented certain new and useful Improvements in an Air-Pump, of which the following is a specification.

The invention relates to a pump structure, and more particularly to the class of air compressors.

The primary object of the invention is the provision of an air compressor of this character, wherein a rocking beam serving 15 as a see-saw has connection with power mechanism for operating the compressor, thus minimizing manual labor or exertion in actuating the power mechanism for multiplying, accumulating and storing power to 20 be used for various purposes for which other and more costly power is at present applied.

Another object of the invention is the provision of an air compressor of this character, wherein the construction thereof is novel in 25 form so that the same can be operated manually in an easy and convenient manner.

A further object of the invention is the provision of an air compressor of this character, which is extremely simple in construction, thoroughly reliable and efficient in its 30 operation, and inexpensive to manufacture and install.

With these and other objects in view, the invention consists in the features of construction, combination and arrangement of parts as will be hereinafter fully described, illustrated in the accompanying drawings and pointed out in the claim hereunto appended.

40 In the accompanying drawing the view represents a vertical sectional view showing the power mechanism in side elevation of the air compressor constructed in accordance with the invention.

45 Referring to the drawing in detail A designates a portion of a tank having an inlet pipe B leading thereto for conveying fluid under compression therein, the pipe B being fitted with a check valve device C of 50 any approved type so as to permit the fluid to pass into the tank or cylinder A and to prevent the same from escape therefrom through said pipe or the return of the fluid therethrough.

55 Adapted to be arranged adjacent to the tank A is the power mechanism which com-

prises a base frame 5, constructed in any desirable manner and having substantially medially thereof a pedestal 6, it being understood of course that two of said pedestals 60 are employed directly opposite each other, while in the drawing but one of the pedestals is shown. Journaled in the pedestal 6 transversely of the base frame 5 is a rock shaft 7 to which is connected a rocking beam 8, the 65 latter serving as a see-saw and has mounted near opposite ends thereof seats 9 to be occupied in the operation of the see-saw.

Journaled transversely of the frame 5 are spaced parallel driving and driven shafts 70 10 and 11 respectively, the shaft 10 being fitted with a main sprocket wheel 12 over which is trained an endless sprocket chain 13 the same being also trained over a secondary sprocket wheel or pinion 14 which 75 is fixed to the shaft 11, the latter being also fitted with a belt wheel or pulley 15 over which is trained an endless belt 16 which has power transmission connection with an eccentric operating shaft 17 which is suitably journaled and supported upon the base frame 5 and carries an eccentric 18 encircled by an eccentric strap 19 which latter has connection with the piston rod 20 of an air compressor or pump 21, the same being 80 formed with a lead or outlet pipe 22 connected with the casing of the check valve device C so as to establish communication with the pipe B of the boiler A, whereby on the operation of the compressor or pump 21 the 85 elastic fluid will be forced into the tank A 90 as will be clearly apparent.

Mounted on the shaft 10 is a disk 24 carrying a wrist pin 25 to which is connected a link 26, the wrist pin 25 being eccentrically mounted on the disk 24 and said link 26 is pivoted at 27 to one end of a lever 28, the same being pivoted at 29 in the base frame 5, the lever 28 being formed with a plurality of spaced holes 30 and likewise 95 the rocking beam 8 is formed with a plurality of spaced holes 31 for the adjustable connection of the connecting pivot 32 with said lever 28 and rocking beam 8 respectively, the pivot 32 being designed to connect the said beam 8 and lever 27 through the medium of an arm 33 so that on the rocking of the beam 8 motion will be imparted to the lever 28 and the said motion of the latter will be transmitted to the shaft 10, 100 thereby converting the rocking motion into rotary motion, which latter is transmitted 105 110

to the shaft 17 and thence the eccentric 18 reciprocates the piston rod 20 of the pump or compressor 21 for actuating the same.

The seats 9 on the rocking beam 8 are to be occupied by operators which manually actuate the said see-saw when the proper compressor is to be operated.

From the foregoing it is thought that the construction and manner of operation of the compressor will be clearly understood and therefore a more extended explanation has been omitted.

What is claimed is:

In a motor, a base, spaced transverse
15 shafts journaled upon said base, a pedestal

rising from the base, a see-saw beam mounted upon the pedestal, a large sprocket gear fixed to one of the shafts, a relatively small sprocket gear fixed to the other shaft, an endless sprocket chain trained over the 20 gears, a disk formed on the shaft having the larger gear, a wrist pin mounted eccentrically in the disk and having a link, a swinging lever pivoted at its end to the base and link respectively, and an adjustable 25 connection between the beam and lever.

In testimony whereof I affix my signature hereto.

MOSES H. HAMILTON.
